UNITED STATES PATENT OFFICE

ST. JOHN WOOD, OF NEW YORK, N. Y.

DESIGN FOR A CUT STONE.

SPECIFICATION forming part of Design No. 36,142, dated November 18, 1902.

Application filed October 4, 1902. Serial No. 126,995. Term of patent 14 years.

To all whom it may concern:

Be it known that I, ST. JOHN WOOD, of New York, in the county of New York, and in the State of New York, have invented a certain 5 new, original, and ornamental Design for a Cut Stone; and I do hereby declare that the following is a full, clear, and exact description thereof, reference being had to the accompanying drawings, in which—

10 Figure 1 is a plan view of a cut stone embodying my invention, and Fig. 2 a side elevation of the same.

The object of my invention is the production of a new, original, and ornamental design 15 for a cut stone; and to this end my invention consists in the design for a cut stone, substantially as herein specified.

My design, viewed in plan, comprises a circular series of triangular or three-sided figures *a*, which radiate from the center of the 20 stone, the pointed ends of the figures meeting at the stone-center, and a second circular

series of quadrilateral figures *b*, that also radiate from the center of the stone, alternating with the three-sided figures *a*. The figures *b* 25 extend beyond the figures *a*, and radiating from between the extended portions of adjacent figures *b* and reaching to the girdle of the stone is a circular series of pentagonal figures *c*, two sides thereof converging to a 30 point that meets at the girdle of the stone. Lying between the points of each adjacent pair of figures *c* is a pair of triangular figures *d*.

Having thus described my invention, what 35 I claim is—

The ornamental design for a cut stone, substantially as herein shown and described.

In testimony that I claim the foregoing I have hereunto set my hand.

ST. JOHN WOOD.
